UNITED STATES PATENT OFFICE.

CHARLES E. McMANUS, OF NEW YORK, N. Y.

MACHINE FOR CUTTING DISKS.

1,259,887.

Specification of Letters Patent. Patented Mar. 19, 1918.

Application filed September 25, 1914. Serial No. 863,486.

To all whom it may concern:

Be it known that I, CHARLES E. McMANUS, a citizen of the United States, residing at No. 25 Fort Washington avenue, 5 borough of Manhattan, city, county, and State of New York, have invented certain new and useful Improvements in Machines for Cutting Disks, of which the following is a specification, reference being had therein 10 to the accompanying drawings.

My invention relates to improvements in slicing machines and particularly those for cutting disks from cylindrical rods of cork. The object of my invention is to provide certain 15 details of construction for disk cutting machines of the rotary magazine type to prevent the cutting of imperfect disks.

In the accompanying drawings

Figure 1 is a plan view showing rotary 20 table and knives.

Fig. 2 is a perspective of feeding and centering devices.

Fig. 3 is a front view of feeding device shown in Fig. 2.

Fig. 4 is a cross-section on line 4—4 of 25 Fig. 5.

Fig. 5 is a bottom plan view, with knife removed, of Fig. 4.

Fig. 6 is a sectional view on line 6—6 of 30 Fig. 5.

Fig. 7 is a detail view of one of the centering jaws.

Fig. 8 is a bottom plan view, partly in section, of a modification of the gripping device.

Figs. 9 and 10 are details of another modification of the gripping device.

Fig. 11 is a vertical section of one of the feeding tubes showing additional centering 40 device.

Fig. 12 is a sectional view of another modification of gripping device on line 12—12 of Fig. 13.

Fig. 13 is a sectional view on line 13—13 45 of Fig. 12.

The rotary table, A, is provided with a plurality of apertures A' adjacent to its periphery in which are fitted tubes B as supports for the cork rods. The rotary 50 knives, C, are provided with wipers, c.

The following is a description of the feeding device. A pair of grippers or corrugated disks, D D', are mounted on shaft d, in supports, e, secured to the table, A. The 55 disk D is fixedly secured to the shaft while the disk D' is loosely mounted thereon by

means of a sleeve having a slot, f, therein, which fits a pin on the shaft to prevent the turning of the disk on the shaft but to allow of lateral movement along the same. A 60 spring, F, bears against the disk, D'. By this arrangement it will be seen that the rod is continuously gripped by the disks, and that rods of different diameters will be gripped by them. A ratchet wheel, H, is secured to the outer end of shaft, d, and is operated by pawl, J, pivoted to supports, K K, loosely mounted on the shaft on either side of the ratchet wheel. As the table revolves the pawl is thrown into engagement with the 70 ratchet by trips, L, the disks are moved through the proper arc and the rod forced downward the required distance.

In the cutting of disks from rods it is important that the disks be of uniform thickness. If the rod turns as it will under the action of the knife unless means are provided to prevent, a wedge-shaped disk results. To prevent the turning mentioned I insert at the base of the apertures A' a 80 ribbed ring W. The action of the feeding device as well as of the knife is to force the rod against the opposite wall and thus against the ribs which hold it against turning. The modification shown in Figs. 12 85 and 13 embraces ring W, but having ribs only on a portion of its inner circumference as shown, and spring Y which presses the rod against the ribs. In the device shown in Figs. 12 and 13, the last end of the rod is 90 held for cutting so that the final remnant if any is less than the required thickness of the disks being cut and not greater, thus avoiding the necessity of sorting out thick disks. The modification shown in Fig. 8 95 consists of pivoted arm S, carrying loosely mounted corrugated sleeve s, which latter is kept in contact with the rod by means of spring t. If the ribs are toothed like a saw they take a firmer grip.

The centering device (shown in Figs. 4 and 5) is designed to permit the cutting of rods of different diameters in the same tube. Toothed rings, M M, provided with oblique slots, m, are fitted in the table around the 105 aperture A' and above and below bushing P which is provided with recesses p' for jaws N provided with pins, n, which are engaged by slots m. The rings are adapted to be turned any desired distance by the operation 110 of the cog wheel, o, engaging the teeth of the rings. As the rings are turned the jaws

are forced inward or outward by the action of the oblique slots on the pins of the jaws. Thus a rod smaller than the tube can be held in proper position for cutting.

5 The jaws are provided with vertical corrugations to hold the rod against turning by the action of the knife.

It is also found that, if the rod tilts as is quite likely when rods smaller than the tube 10 are being cut, wedge-shaped disks are produced. To overcome this I employ the device shown in Fig. 11, consisting of the hinged eccentric R arranged to operate through slot r in the tubes and adjusted by 15 means of set screw x so as to hold the rod the required distance away from the side of the tube. This device is located opposite the feeding disks which in action force the rod away. Thus the rod is retained in center as it is practically supported at four 20 points, two by the disks themselves, one by their forcing action, and one by the eccentric R.

I claim:

25 1. In a machine for cutting slices from rods, a pair of rotatable disks arranged in

planes tangential to the rod and adapted to grip the rod between their faces and advance the same when rotated.

2. In a machine for cutting slices from 30 rods, a pair of disks mounted on a shaft tangentially to the corresponding rod, one of said disks fixedly mounted on said shaft, the other loosely mounted thereon so as to permit of a lateral motion but rotating with 35 the shaft, means for pressing the same toward the fixed disk so as to grip the rod, and means for rotating said shaft.

3. In a machine for cutting slices from 40 rods, a pair of disks rotatably mounted in substantially parallel perpendicular planes tangentially to the corresponding rod and adapted to grip the rod between their inner faces, means for maintaining a gripping pressure on at least one of said disks, and 45 means for rotating said disks through a predetermined arc.

CHARLES E. McMANUS.
